UNITED STATES PATENT OFFICE.

CHRISTOPHER S. BOOTH, OF CAMP POINT, ILLINOIS.

WRITING INSTRUMENT.

Application filed May 23, 1921. Serial No. 471,952.

To all whom it may concern:

Be it known that I, CHRISTOPHER S. BOOTH, citizen of the United States, residing at Camp Point, in the county of Adams 5 and State of Illinois, have invented a certain new and useful Improvement in Writing Instruments, of which the following is a full, clear, concise, and exact description.

My invention relates to pens and pencils, 10 generically classed as writing instruments, and resides in the provision of improved attaching clips therefor. The attaching clip of my invention is suitably assembled with the writing instrument and there is employed in conjunction therewith unitary means for positioning the clamping end of the clip toward and from the writing instrument whereby the clip may be clamped to the clothing or release its hold upon the 15 clothing as desired.

In the preferred embodiment of the invention a mounting is provided upon the writing instrument for one end of the attaching clip, this mounting having an exterior cylindrical surface whose axis is inclined with respect to the writing instrument and which cylindrical surface is engaged by the clip and operates thereupon to position the other end of the clip closer to 20 or further from the writing instrument according to the position of the clip with respect to its mounting.

I will explain my invention more fully by reference to the accompanying drawing 25 in which Fig. 1 is a view in side elevation illustrating a pencil equipped with the preferred form of my invention, the clip being shown in full lines as being in gripping engagement with the outer wall of a vest pocket and being shown in dotted lines as 30 being released from such engagement; Fig. 2 is a view illustrating a part of the structure in perspective and a part in sectional elevation, one position of the clip being 35 shown in full lines and the other in dotted lines; Fig. 3 is a view of the clip in elevation as it appears in Fig. 1 taken at right angles to the direction in which Fig. 1 is taken; Fig. 4 is a sectional view on line 40 4—4 of Fig. 1 minus the pocket, the clip being shown in this figure in clamping position; Fig. 5 is a view similar to Fig. 4 with the clip in unclamping position.

Like parts are indicated by similar characters of reference throughout the different figures.

The writing instrument illustrated is in the form of a pencil, though it is to be understood that the clip of my invention may be applied to a pen as well as a pencil. 60 A clip mounting is slipped upon the pencil, the mounting illustrated being in the form of a sleeve 2 having longitudinal slots 3 therein that form the sides and ends of the sleeve into spring fingers that are inwardly 65 pressed into spring engagement with the writing instrument, the sleeve being movable longitudinally along the writing instrument and being held in any position to which it is placed by the spring clamping 70 action of the split portion of the sleeve. An intermediate portion 4 of the sleeve has its axis inclined with respect to the axis of the balance of the sleeve and the axis of the writing instrument. That is, a part of the 75 bore of the sleeve is co-axial with the writing instrument and the part at 4 has its axis inclined with respect to the axis of the writing instrument. The exterior surface of the mid sleeve section 4 is cylindrical, this 80 cylindrical surface being also inclined with respect to the writing instrument to correspond with the bore of the sleeve section. It is this mid section of the mounting sleeve with which the clip 5 is directly assembled, 85 the upper end of the clip being preferably in the form of a split cylindrical sleeve 6 that is in spring gripping engagement with the exterior cylinder surface of the sleeve section 4. This sleeve section 4 is formed with 90 a flange 7 at its lower end and a flange section 8 at its upper end. This flange may be either brazed or spun on the sleeve section 4. The clip end 6 is disposed between the flange portions 7 and 8 so that the clip 95 is not movable lengthwise of the writing instrument with respect to its mounting sleeve. The lower end of the clip is desirably formed with a knob 9 which is to press upon the cloth wall 10 of a pocket 11 in which 100 the writing instrument is carried. To bring the gripping end 9 of the clip into and out of engagement with the pocket, the clip and its mounting are relatively turned. The element which is actually turned is preferably the clip mounting, the clip itself being held from material rotation by its engagement with the pocket.

In preparing the writing instrument for reception in the pocket the upper end of the 110 clip is held and the writing instrument is turned to make the space between the clamp-

ing end 9 of the clip and the pencil as wide as possible, as indicated in dotted lines in Figs. 1 and 2. When a wall of the pocket has been interposed between the lower end 5 of the clip and the writing instrument the writing instrument is turned in a reverse direction whereby the clamping end 9 of the clip is forced against the wall of the pocket and forces this wall of the pocket against 10 the writing instrument whereby the writing instrument is held in firm assembly with the pocket to prevent accidental withdrawal thereof.

The flange section 8, in addition to preventing upward movement of the clip upon 15 and with reference to its mounting, also serves as a stop to confine the upper end of the clip to a large range of rotation in which the lower end of the clip is applied to or 20 removed from the interposed pocket wall.

The illustrated mounting of the clip preferably also constitutes unitary means for 25 positioning the clamping end of the clip toward or from the writing instrument, but I do not wish to be limited to the employment of a mounting which also serves as an adjustment means.

While I have herein shown and particularly described the preferred embodiment of 30 my invention I do not wish to be limited to the precise details of construction shown as changes may readily be made without departing from the spirit of my invention, but having thus described my invention I claim 35 as new and desire to secure by Letters Patent the following:

1. The combination with a writing instrument; of an attaching clip; and a mounting upon the writing instrument with which 40 mounting one end of the clip is movably assembled, said mounting being formed at one place of engagement of the clip therewith to place the other end of the clip closer to the writing instrument and at another place of engagement of the clip therewith to place 45 said other end of the clip further from the writing instrument.

2. The combination with a writing instru-

ment; of an attaching clip; and a mounting upon the writing instrument with which 50 mounting one end of the clip is movably assembled, said mounting having a cam portion in engagement with the clip to position the other end of the clip closer to or further from the writing instrument according to 55 the relative position of the clip and mounting.

3. The combination with a writing instrument; of an attaching clip; and a mounting upon the writing instrument for one end of 60 the clip, this mounting having an exterior cylindrical surface whose axis is inclined with respect to the writing instrument and which cylindrical surface is engaged by the clip and operates thereupon to position the 65 other end of the clip closer to or further from the writing instrument according to the position of the clip with respect to its mounting.

4. The combination with a writing instrument; of an attaching clip; and a mounting upon the writing instrument for one end of 70 the clip, this mounting having an exterior surface similarly inclined on opposite sides of and with respect to the writing instrument and which surface is engaged by the 75 clip and operates thereupon to position the other end of the clip closer to or further from the writing instrument according to the position of the clip with respect to its mounting.

5. The combination with a writing instrument; of an attaching clip assembled with the writing instrument; and an adjusting device upon the writing instrument, said adjusting device being formed at one place of engagement of the clip therewith to place the other end of the clip closer to the writing instrument and at another place of engagement of the clip therewith to place 85 said other end of the clip further from the writing instrument.

In witness whereof, I hereunto subscribe my name this 11th day of May, A. D., 1921.

CHRISTOPHER S. BOOTH.
